DESIGN FOR A SUCTION CLEANER CASING

George W. Walker, Pleasant Ridge, Mich., assignor to Eureka Williams Corporation, a corporation of Michigan

Application May 21, 1945, Serial No. 119,649

Term of patent 14 years

(Cl. D9—2)

To all whom it may concern:

Be it known that George W. Walker, a citizen of the United States of America and a resident of Pleasant Ridge, in the county of Oakland and State of Michigan, has invented a certain new, original, and ornamental Design for Suction Cleaner Casing, of which the following is a specification, reference being had to the accompanying drawings, of which there are two sheets, forming a part thereof and wherein:

Fig. 1 is a side elevational view of a suction cleaner casing embodying my design;

Fig. 2 is a plan view thereof;

Fig. 3 is a rear elevational view thereof;

Fig. 4 is a front elevational view thereof;

Fig. 5 is a perspective view thereof taken from the rear; and

Fig. 6 is a perspective thereof taken from the front.

The essential features of my design reside in the parts shown in full lines.

The stippling shown in the drawings is for purposes of shading only.

I claim:

The ornamental design for a suction cleaner casing, substantially as shown and described.

GEORGE W. WALKER.
